 Ohio, a corporation of Ohio

Application September 7, 1937, Serial No. 162,622

19 Claims. (Cl. 51—95)

This invention relates to machine tools and more particularly to improvements in grinding machines.

One of the objects of this invention is to provide an improved automatic infeed cycle mechanism for grinding machines.

Another object of this invention is to so contrive an automatic hydraulic infeed cycle mechanism that it may be push button controlled for starting purposes.

A further object of this invention is to provide an automatic infeed cycle mechanism having variable means for predetermining the variable elements of the cycle such as the total length of stroke, the length of the rapid traverse approach movement, the rate of the feeding movement and the length of tarry before the retracting movement takes place.

An additional object of this invention is to provide an improved hydraulic control circuit for an infeeding mechanism of a grinding machine.

Other objects and advantages of the present invention should be readily apparent by reference to the following specification, considered in conjunction with the accompanying drawings forming a part thereof and it is to be understood that any modifications may be made in the exact structural details there shown and described, within the scope of the appended claims, without departing from or exceeding the spirit of the invention.

Referring to the drawings in which like reference numerals indicate like or similar parts:

Figure 1 is a front elevation of a grinding machine embodying the principles of this invention.

Figure 2 is a detail sectional view showing the interlocking mechanism between the traversing mechanism and the infeeding mechanism, as viewed on the line 2—2 of Figure 1.

Figure 3 is an end view of the valve block as viewed on the line 3—3 of Figure 1.

Figure 4 is a section through the valve block as viewed on the line 4—4 of Figure 3.

Figure 5 is a section through the gearing shown in Figure 4 as viewed on the line 5—5 of that figure.

Figure 6 is a sectional view through the machine as viewed on the line 6—6 of Figure 1.

Figure 7 is an enlarged detail view through a rate control valve.

Figure 8 is a diagrammatic view of the hydraulic control circuit.

Referring to Figures 1 and 6 of the drawings the reference numeral 10 indicates the bed of

a grinding machine in which is embodied the principles of this invention. The grinding wheel support 11 and the work support or work table 12 are mounted for relative traversing movement and for relative infeeding movement whereby either traverse grinding or infeed grinding may be performed on the machine. For purposes of illustration the grinding wheel support 11 is fixed with the bed 10 and the table 12 executes the movements, it being guided on ways 13 and 14 for traversing movement and these ways are formed on a saddle 15 which, in turn, is supported on ways 16 and 17 as shown in Figure 1 for moving the table 12 toward and from the grinding wheel 18 which is rotatably mounted on the support 11.

It will be understood that both of these movements could be imparted to the grinding wheel or either one of the movements imparted to the grinding wheel and the remaining movement imparted to the work support without departing from the principles of this invention.

Any suitable form of known traversing mechanism may be provided for traversing the table 12 but for illustrative purposes a cylinder 19 having a contained piston 20, which is connected by a piston rod 21 to the table, is illustrated as constituting one suitable form, and it will be understood that a hydraulic control circuit which is not shown may be provided for governing operation of the table 12 and having a start and stop control lever which is indicated in Figure 2 by the reference numeral 22.

During traverse grinding it is the usual practice to feed the work toward the grinding wheel at the end of each stroke of the table and a conventional pick feed mechanism for this purpose is illustrated in Figure 6. As shown in that figure, a screw 23 which is carried by the saddle 15 has a threaded engagement with a nut 24 which is fixed with the bed 10. This screw has a gear 25 keyed to one end and connected by an idler 26 to a pinion 27 keyed to the reduced end of shaft 28. For micrometric manual adjustment the shaft 28 is provided with a gear 29 which intermeshes with a pinion 30 which is journaled in the housing 31 and formed integral with a shaft 32 upon the end of which is formed a gear 33. This gear intermeshes with a pinion 34 integral with shaft 35 which is keyed to the hand lever 36. By rotation of the hand lever the pinion 34 rotates the gear 33 and thereby through the interconnection of pinion 30 and gear 29 the pinion 27 may be rotated.

The lever 36 may be connected by the handle 35

37 having a reduced end 38 which may be inserted in any one of a plurality of holes 39 formed in the pick feed wheel 40. An oscillatable lever 41 having a pivoted pick feed pawl 42 is provided 5 for indexing the wheel 40 at the end of each stroke of the table in accordance with conventional practice, whereby the work may be fed toward the grinding wheel at the end of each table stroke.

10 Due to the micrometric nature of this pick feed mechanism it is unsuitable for use in effecting an infeeding cycle, and therefore, a separate mechanism has been provided which in no way interferes with the pick feeding mechanism nor with 15 the power traversing mechanism for the table, with the exception that it is interlocked with such mechanism through the start and stop lever 22 shown in Figure 2, whereby power traversing and power infeeding cannot take place at the same 20 time.

The actual movement between the saddle and grinding wheel is effected by a hydraulic motor comprising a cylinder 43 formed integral with the saddle and having a contained piston 44 25 which is directly secured to the end of the lead screw 23, a portion of the lead screw acting in this case as a piston rod. Since the screw 23 cannot move axially without rotation relative to the nut 24 the piston 44 becomes the stationary 30 element and the cylinder 43 the moving element.

The introduction of fluid into the cylinder 43 is controlled by a servo-valve mechanism comprising a servo-valve 45 having a plunger 46 which is continuously held against the end of a control 35 lever 47 by means of a spring 48 mounted in one end of the valve housing. This valve has a pressure port 49, a pair of exhaust ports 50 and 51, and a pair of motor ports 52 and 53 which are located between the pressure port, and the respective 40 exhaust ports 50 and 51. The motor ports 52 and 53 are connected by channels 54 and 55, respectively, to opposite ends of the cylinder 43. The lever 47 is pivotally supported at 56 to the end of a reciprocable plunger 57 whereby, 45 upon axial movement of the plunger the pivot 56 is moved through space. The end 58 of the lever 47 is connected to the screw 23 by interfitting in an annular groove 59 formed on the screw, as shown in Figures 6 and 8. It will now be apparent 50 that if the pivot point 56 is moved in a direction to permit the spring 48 to shift the servo-valve plunger 46 away from its center position that the pressure port 49 will be connected to the motor port 53 and fluid will be introduced into 55 cylinder 43 in a manner to cause movement of the saddle away from the grinding wheel; and since the servo-valve 45 and plunger 57 are carried by the saddle, the pivot point 56 will also be moved with the saddle and furthermore, since 60 the end of lever 47 is fixed with the now immovable screw, a rotation of lever 47 in a clockwise direction about pivot 56 will result, and the servo-valve plunger 46 will be moved back against the compression of spring 48 to close the pressure- 65 port 49. Thus, the servo-valve plunger 46 is caused to follow up the movement of the saddle. Should the plunger 57 be moved relative to its housing 60, while the saddle is stationary, in a downward direction, as viewed in Figure 8, it will 70 cause a clockwise rotation of lever 47, due to the end 58 being fixed, and thereby move the servo-valve plunger 46 downward, connecting port 49 to motor port 52 and thus introducing pressure into the other end of cylinder 43.

75 This will cause the saddle to move toward the

grinding wheel and also cause the pivot point 56 to move in the same direction but in so moving will cause a relative counterclockwise direction of rotation of lever 47 and permit the servo-valve plunger to come back to a central position under 5 the pressure of spring 48 and close the pressure port 49. Thus, regardless of the direction of movement of the plunger 57 to open the servo-valve, the resultant movement of the saddle will cause a follow-up movement to take place which 10 will reposition the servo-valve plunger in a central or stop position.

The housing 60 for the plunger 57 is in fact a rotatable sleeve which is journaled at 61 in the saddle 15, as shown in Figure 5, and held against axial movement by means of a flange formed on one end, and a gear 63 attached to the other end. A pin and slot connection is provided between the sleeve and the plunger whereby, upon rotation of the sleeve, a positive axial movement may be imparted to the plunger. As shown in Figure 8, the groove 64 is spirally cut in the sleeve and a pin 65 fixed with the plunger with its free end entering the groove. Since the plunger is held against rotation it will be apparent that rotation of the sleeve will cause lateral movement of the pin and thereby axial movement of the plunger 57.

The sleeve during an automatic cycle is power rotated and the control circuit shown in Figure 8 controls this power actuation in such a manner 30 as to cause the saddle to execute an automatic cycle including the following steps: rapid traverse approach to grinding position, infeed, dwell to permit the grinding wheel to clean up the work and finish it to desired size, rapid return and stop. 35

The power actuator comprises a hydraulic motor in the form of a cylinder 66 and contained piston 67. As shown in Figure 4, the piston rod 68 projects beyond both ends of the cylinder and on one end is provided with one set of rack teeth 40 69 intermeshing with an idler gear 70, and a second set of rack teeth 71 which intermesh with gear 72. The idler gear 70 meshes with gear 63 previously mentioned as attached to the end of the rotatable sleeve 60. The idler gear 70 has an 45 arcuate slot formed therein into which extends a fixed pin 74 which acts as a means to limit the maximum stroke of the piston 67 in either direction.

The hydraulic circuit shown in Figure 8 serves 50 to automatically control the rate and direction of movement of the piston 67 and to that end, the circuit is provided with a reversing valve 75 which determines the direction of movement of the piston 67; a pilot valve 76 which causes power shifting of the reversing valve; a rate valve 77 which determines the rate of the feeding movement; a tarry valve 78 which determines the length of pause of the grinding wheel while finishing the work to size; a rapid traverse control valve 79 60 which determines the length of the rapid traverse approach movement; and a start and stop valve 80. This circuit is supplied with fluid pressure from a pump 81 which has an intake 82 through which fluid is withdrawn from a reservoir 83, and 65 a delivery pipe 84, which has a branch connection to a relief valve 85. The channel 84 not only supplies fluid pressure to the pressure port 49 of the servo-control valve, but also to ports 86 and 87 of the pilot valve 76, and port 88 of the reverse valve 75.

The plunger 89 of the reversing valve 75 is shown in a position for causing movement of the work toward the grinding wheel and the piston 67 is shown in a starting position ready to start 75

this movement. In this position of the parts the fluid from pressure port 88 will flow through the cannelure 90 of plunger 89 to port 91 which is connected by channel 92 to port 93 of the start 5 and stop control valve 80. This valve has a plunger 94 to the end of which is attached a large push button 95. In the stop position this plunger is to the left of that in which it is shown and in its left position a spool 96 closes port 97, 10 which is connected by channel 98 to port 99 located in the left hand end of cylinder 66.

It will now be apparent that if the operator presses the push button 95 the plunger 94 will move toward the right and into the position in 15 which it is shown in Figure 8. This will connect the port 93, which is already connected to the pump by the reversing valve, to port 97 and thereby to the left end of cylinder 66. The fluid from the other end of the cylinder will re- 20 turn to reservoir through port 100, channel 101, port 102, cannelure 103, port 104, channel 105 to port 106 of the rate valve 77. This valve, how- 25 ever, forms a high resistance to flow in this direction and therefore a check valve 107 in channel 105 will open, permitting the fluid to flow to port 108 of the rapid traverse control valve 79. This 30 valve has a plunger 109 which is threaded at 110 into a yoke 111 which is attached at 112 to the end of piston rod 68, whereby the plunger 109 35 moves simultaneously with the piston 68. The plunger 109 has an annular groove 113 which serves to interconnect port 108 with port 114. Thus, the fluid will continue to flow through port 114 and channel 115 to port 116 of the reversing 40 valve 75. The plunger 89 of the reversing valve is in a position such that the cannelure 117 there- 45 of interconnects port 116 to port 118 which is connected by channel 119 to reservoir. Since the check valve 107 is a low resistance check valve, it will be apparent that the fluid escaping from 50 the right hand end of cylinder 66 has a relatively free passage to reservoir, thus offering very little resistance to the movement of piston 67 whereby the same may move at a rapid traverse 55 rate.

The length of the rapid traverse positioning movement will vary, of course, with the diameter of the work and therefore by providing the threaded engagement of the plunger 109 in the 50 yoke 111 the position of the plunger 109 with respect to the piston 66 may be varied so that the time of closing of port 114 by the spool 120 may be varied. This is because the closing of port 114 will stop the rapid traverse movement in that 55 it will close the open passage to reservoir and cause additional returning oil to be forced through the rate valve 77. In order that the position of plunger 109 may be preset, the end of the plunger is provided with a manually oper- 60 able knob 121 which has an integral sleeve 122 telescoping the nut portion 123 of the yoke and the surface of this may be graduated in conjunction with suitable graduations formed on the tapered end of the sleeve 122 in the nature of a 65 micrometer to predetermine the length of the rapid traverse movement.

The rate valve 77 has a plunger 124 which is threaded at 125 in the end of the housing and provided with a manually operable handle 126, 70 whereby longitudinal position of the plunger and the housing may be varied. This is for the purpose of varying the position of V notches 127 formed on the valve spool 128 with respect to the port 106 to thereby change the resistance of this 75 port to the escape of fluid to reservoir and there-

by the rate of the feeding movement. The fluid passing through this resistance accumulates in annular groove 129 which is in communication with port 130 whereby fluid will continue through channel 131 to port 116 of the reversing valve and thereby to reservoir. It will now be noted that the rapid traverse control valve and the rate valve are connected in parallel between the port 104 of the start-stop valve 80 and the port 116 of the reversing valve whereby the fluid flows part of the time through the low resistance circuit including the rapid traverse valve and then when this valve closes, the fluid goes through the high resistance circuit including the rate valve whereby the rapid traverse movement is slowed down to 10 feed rate.

The feeding movement continues until another portion 132 of the yoke 111 pulls the plunger 133 of the pilot valve 76 toward the right as viewed in Figure 8. The plunger 133 has a reduced portion 134 which passes through a hole 135 in the yoke whereby the yoke may move with respect to the plunger until it hits an adjustable dog 136 secured to the plunger. By changing the position of this dog it will be apparent that the point 25 of reversal may be changed, or in other words, the size of the work determined.

When the plunger 133 is shifted to the right it disconnects the pressure port 87 from port 131 which is connected by channel 138 to the 30 left end of reversing valve housing 75. In addition, it connects pressure port 86 to port 139, which, in turn, is connected by channel 140 to ports 141 and 142 of the tarry valve 78, and it will be noted that the central spool 143 of 35 the plunger 133 is larger in diameter than the end spools whereby after the port 86 is cracked and pressure fluid flows into the annular groove 144, the pressure differential created by the difference in end area of the opposing spools will 40 complete the shifting movement in the manner of a load and fire mechanism. Completion of this shifting movement will result in port 137 being connected to reservoir port 145 whereby the left end of the reversing valve housing 75 45 is open to reservoir so that upon admission of pressure to port 146 the plunger 89 will be shifted to the left. The port 146 is connected by channel 147 to port 148 of the tarry valve. This 50 valve is constructed exactly the same as the rate valve whereby the port 141 is connected through a high resistance to port 148 so that fluid will flow through there at a slow rate. The resistance of the tarry valve will, of course, be higher than the rate valve in order that an appreciable 55 time will pass before sufficient fluid pressure is built up in the right hand end of the reversing valve to cause shifting of its plunger.

In spite of the shifting of the pilot valve plunger, no change has been made in the operating circuit and the piston 67 still continues to move. A positive stop has been provided to function at this point so that even though the piston 67 continues to move it will merely cause an increase in the pressure in cylinder 43 without causing further movement of the saddle. This stop positively determines the size of the work and is adjustable independently of the operating mechanism for varying the size of the work. This positive stop comprises a thrust 70 bearing 149 which is mounted between the cylinder head 150 of the cylinder 43 and a loose washer 151 which is supported on a reduced portion 152 of the screw 23 for movement relative thereto. The washer is adapted to fit in a coun- 75

tersink 153 formed in the end of the hub of gear 25, which gear is fixed against axial movement with respect to the saddle 15. The screw has an enlarged splined portion 154 by means of which the gear 25 is connected for rotation of the screw while permitting relative axial movement therebetween. The splined portion 154 forms a shoulder 155 against which the washer 151 is adapted to abut during inward movement 10 of the saddle relative to the screw, thus forming a positive stop to the inward movement of the saddle.

If it is desired to change the size of the work being ground, the screw 23 may be rotated 15 through the gear 25 by means of the mechanism shown in Figure 6 and since the screw is threaded in the fixed nut 24 it will move axially and thereby change the position of the shoulder 155 in space and thereby change the stop position of 20 the saddle.

It will now be evident that even although the reversing valve is not immediately shifted by the tripping of the pilot valve and that the piston 67 still continues to move a small amount, the size 25 of the work has been accurately determined and it is merely necessary to allow sufficient time for the grinding wheel to spark out before the reversing valve is fired. The amount of this time is determined by the setting of the tarry 30 valve and eventually it will effect shifting of the reversing valve into its left hand position.

When this has been accomplished, the port 35 88 will be connected to port 116 and fluid pressure will flow to the port 130 of the feed rate control valve 77. Fluid pressure flowing in this direction will pass into the annular groove 129 and through diametrical passages 156 into an axial bore 157. One end of this bore is closed by a spring pressed ball 158 which acts as a check 40 valve. Pressure coming in this direction will easily open this check valve and the fluid pressure will flow past the ball and out through radial holes 159 into annular groove 160 and thereby to port 161. This port is connected by channel 45 105 to port 104 of the start and stop valve whereby the fluid will continue through annular groove 103, port 102 and channel 101 to port 100 located in the right hand end of cylinder 66. Since the check valve in the rate control valve is a low 50 pressure check valve, it will be apparent that there is very little resistance to the flow of fluid and therefore the piston 67 will move back at a rapid rate. The return fluid from the other end of the cylinder will return to reservoir 55 through port 99 located in the left end of the cylinder 66, interconnected ports 97 and 93 of the starting valve 80, channel 92, interconnected ports 91 and 162 of the reversing valve to the return channel 163.

60 Near the end of the rapid return movement of piston 67, the pilot valve 133 will be shifted into the position in which it is shown in Figure 8. This will reconnect pressure port 81 to port 137 whereby the fluid will flow through channel 138 65 to annular groove 164 in which is formed two sets of radial ports 165 and 166. At the moment, port 166 is connected to port 161, due to the fact that the plunger 89 is in its left hand position. This will cause the pressure fluid to flow through 70 channel 168 and past the low pressure check valve 169 to channel 170 which leads to the right hand end of the start and stop valve 80. The end of this valve is also connected by a high fluid resistance coil 171 to return channel 172. 75 The result of this is that the shot of high pres-

sure fluid into channel 170 will shift the valve plunger 94 into a stop position which will disconnect ports 93 and 97. At the same time, fluid will be flowing through port 165 into the left hand of valve 75 and immediately afterward 5 will shift the plunger 89 to the right. The delay in movement will be caused by forcing the fluid in the right hand end of the cylinder through channel 147 and the tarry valve 78. This valve is constructed the same as the valve 10 shown in Figure 7 with the exception that the spring which holds the check ball is made stronger so that this valve will not open before the check valve 169 opens. Thus, it is possible to cause the stop and start valve to move to a stop 15 position before the reversing valve is shifted. The returning fluid from port 142 of the tarry valve 78 will pass through channel 140, interconnected ports 139 and 173 to return channel 163. Thus, the circuit is reconditioned for an- 20 other cycle.

It will be noted that when the start and stop valve plunger 94 is in its stop position that ports 97 and 102 will be interconnected and thus condition the circuit so that the piston 67 may be 25 moved manually without resistance to the fluid in either end of cylinder 66 because upon movement of piston 67 the fluid in one end of the cylinder will merely flow to the other end.

The mechanism for manually moving the servo-valve to cause in and out movement of the saddle is shown in Figure 5 and comprises a manually operable lever 174 which is keyed at 175 to a clutch member 176. This clutch member is normally held out of engagement with a clutch member 177 which is pinned to the shaft 178 to which is fixed the gear 72. This is effected by a spring 179 which is interposed between the two clutch members, and to prevent inadvertent engagement of the clutches a spring pressed plunger 180 is reciprocably mounted in a boss 181 formed integrally with the handle 174, and the end of the plunger has a reduced portion 182 which is adapted to engage a notch formed in the end of shaft 178. When it is desired to effect manual 40 operation, the operator pulls out the plunger 180 by means of the knob 183 formed on the end thereof and pushes inwardly on the handle to effect engagement of the clutch members. These parts have to be held together during manual operation and when they are released they will return to the position shown in Figure 5, and thereby insure against inadvertent operation during power actuation of the device.

When it becomes necessary to true the wheel the 55 trueing tool is mounted on the saddle and the saddle is moved inward to the limit of its stroke and held in that position during reciprocation of the table. This is accomplished by providing a pivoted latch member 184 which swings about a 60 pin 185 as shown in Figure 3 and the end of the latch member has a slot 186 cut in one side thereof so that it may fit down over the rod 134. During the automatic operation of the cycle, as 65 previously explained, the latch is in the position shown in Figure 3. Upon rotation of this latch in a counterclockwise direction, as viewed in Figure 3, it will be withdrawn from its position between the yoke 111 and the trip dog 136. This means that the piston 67 can move to the end of 70 its stroke as determined by the stop pin 74 without the yoke 111 engaging the trip dog 136. Thus, the saddle will move in and be held in that position by hydraulic pressure. After the 75 trueing operation has been completed the opera-

tor manually shifts the pilot valve by grasping the dog 136, which, in turn, will eventually cause shifting of the reversing valve and return movement of the parts to a starting position. In order to insure that the infeeding cycle is not thrown into operation while the table is traversing, an interlock has been provided between the starting member 22 for the reciprocating cycle and the infeeding mechanism. This interlock is shown in Figure 2 and comprises a lever 187 which is centrally pivoted at 188 and connected at one end by a pin 189 to a starting lever 22 and at the other end by a pin 190 to an interlock plunger 191. This plunger has a notch 192 formed therein for receiving an interlocking pin 193. This pin is adapted to engage a notch 194 formed in the periphery of gear 63 secured to the end of sleeve 60. It will be noted that the pin 193 is of such length that it will prevent simultaneous actuation of both mechanisms.

There has thus been provided an improved automatic infeed mechanism for a grinding machine, while although hydraulic in nature, has a push button type of starter, and which includes means for adjusting all of the variable elements involved in such a cycle, and which will automatically stop after a cycle has been completed.

What is claimed is:

1. In a grinding machine having a work support and a grinding wheel support and a cooperating screw, and a nut mounted on the respective supports, a piston integral with said screw, a cylinder enclosing said piston and attached to one of said supports, a servo-control valve having fluid connections to said cylinder, a power operable member for actuating said servo-valve, and a one-cycle control circuit for said power operable member including a starting valve for coupling pressure to said member, and means operable at the end of the cycle for repositioning said valve in a stop position.

2. In a grinding machine having a grinding wheel and a work support, the combination of an infeeding mechanism for effecting relative movement between said supports including a servomotor control mechanism, a fluid operable piston operatively connected for control of said servomotor mechanism, a one-cycle fluid control circuit for said piston including a start and stop valve, manually operable means for shifting said valve to a running position, and fluid operable means automatically effective at the end of a cycle for repositioning said valve in a stop position.

3. In a grinding machine having a grinding wheel and a work support, the combination of a hydraulic servo-motor including a control valve for feeding one of said supports relative to the other, a fluid operable piston, motion transmitting means coupling said piston for movement of said servo-valve whereby the rate of movement of said piston will determine the rate of movement between said supports, and a hydraulic control circuit for said piston including means for causing a rapid movement and then a feeding movement, and means for automatically changing the rate from one to the other.

4. In a grinding machine having a grinding wheel and a work support, the combination of means for effecting relative movement between the supports to effect a grinding operation including a first fluid operable motor, a rate and direction control valve therefor, a second fluid operable motor for actuating said valve, and a fluid control circuit for said second motor including

means for automatically changing the unidirectional rate of movement thereof, and subsequently operable means for changing the direction of movement thereof.

5. In a grinding machine having a grinding wheel and a work support, the combination of an automatic infeeding mechanism therefor including a hydraulic motor, a servo-control valve mechanism, a fluid operable motor for actuating said servo-valve, a fluid control circuit for said last-named motor including a feed rate control valve and a rapid traverse control valve connected in parallel in said circuit, means to connect said rapid traverse valve for movement by said fluid operable motor, said means including an adjustable connection for varying the time of closing of said rapid traverse valve and thereby varying the length of the rapid traverse movement.

6. In a grinding machine having a grinding wheel support and a work support, the combination of transmission means for effecting an automatic cycle of relative movement between said supports including rapid traverse advance, feed and rapid return, comprising a servo-motor and control valve, a fluid operable piston for moving said control valve, an operating circuit for said piston including a reversing valve, a pilot control valve for said reversing valve, a rapid traverse control valve, and a feed rate control valve connected in parallel between said reversing valve and said piston, means positively connecting said rapid traverse valve for movement with the piston, a lost motion connection between the piston and pilot valve whereby during movement of the piston in one direction the rapid traverse rate may be changed to a feed rate, and the pilot valve may be shifted to change the direction of said movement.

7. In a machine tool having a work support and a tool support, the combination of power operable means for effecting relative movement between the supports including a reverser, fluid operable means for shifting said reverser including a pilot valve, a control member means for moving said member in proportion to the rate of movement between said supports, a lost motion connection between said member and the pilot valve for tripping same, and means to disconnect the member and valve to prevent tripping of the pilot valve.

8. In a machine tool having a pair of relatively movable supports and power operable means for effecting a limited movement therebetween, the combination of a fluid operable member for controlling the rate and direction of said movement, said member having positive means for limiting its movement in each direction, a control valve effective to change the direction of movement of said member, a lost motion connection between said member and the control valve for effecting tripping of the latter, and means to enlarge said lost motion whereby the member will reach the end of its stroke without tripping said control valve.

9. In a machine tool having a pair of relatively movable supports and fluid operable control means for effecting said relative movement, the combination of a hydraulic control circuit including a reversing control valve and a stop control valve, fluid operable means for shifting said valves, individual check valves through which fluid must flow to cause shifting of the respective control valves, one of said check valves being set to a higher resistance than the other whereby upon application of fluid pressure to the check

valves one of said control valves will be shifted ahead of the other.

10. In a machine tool having a work support and a tool support, power operable means for effecting relative movement between the supports including a hydraulic motor, a servo-control for said motor including a reciprocable plunger, a rotatable member enclosing the plunger, one of said parts having a spiral slot therein and the other a pin engaged in the slot whereby rotation of the member will effect translation of the plunger, and an auxiliary hydraulic motor for effecting rotation of the member.

11. In a machine tool having a work support and a tool support, power operable means for effecting relative movement between the supports including a hydraulic motor, a servo-control for said motor including a reciprocable plunger, a rotatable member enclosing the plunger, one of said parts having a spiral slot therein and the other a pin engaged in the slot whereby rotation of the member will effect translation of the plunger, an auxiliary hydraulic motor for effecting rotation of the member, and means for determining the rate and direction of operation of said second hydraulic motor.

12. In a machine tool having a work support and a tool support, power operable means for effecting relative movement between the supports including a hydraulic motor, a servo-control for said motor including a reciprocable plunger, a rotatable member enclosing the plunger, one of said parts having a spiral slot therein and the other a pin engaged in the slot whereby rotation of the member will effect translation of the plunger, an auxiliary hydraulic motor for effecting rotation of the member, and means for determining the rate and direction of operation of said second hydraulic motor, said means including a pilot control valve and operative connections between said second hydraulic motor and said pilot valve for actuation of the valve by the motor.

13. In a machine tool having a work support and a tool support, power operable means for effecting relative movement between the supports including a hydraulic motor, a servo-control for said motor including a reciprocable plunger, a rotatable member enclosing the plunger, one of said parts having a spiral slot therein and the other a pin engaged in the slot whereby rotation of the member will effect translation of the plunger, an auxiliary hydraulic motor for effecting rotation of the member, means for determining the rate and direction of operation of said second hydraulic motor, said means including a pilot control valve and operative connections between said second hydraulic motor and said pilot valve for actuation of the valve by the motor, and adjustable means for varying the phase reaction of said motor on the valve.

14. In a machine tool having a work support and a tool support, power operable means for effecting relative movement between the supports including a first hydraulic motor, a servo-motor valve mechanism for controlling the feeding movement of said hydraulic motor, a second hydraulic motor for operating said servo-motor mechanism, and means for controlling the rate of actuation of said second motor including an adjustable feed rate determining valve, a rapid traverse selector valve, and operative connections between the second hydraulic motor and said last-mentioned valve for controlling effective positioning of said valve.

15. In a machine tool having a work support

and a tool support, power operable means for effecting relative movement between the supports including a first hydraulic motor, a servo-motor valve mechanism for controlling the feeding movement of said hydraulic motor, a second hydraulic motor for operating said servo-motor mechanism, and means for controlling the rate of actuation of said second motor including an adjustable feed rate determining valve, a rapid traverse selector valve, operative connections between the second hydraulic motor and said last-mentioned valve for controlling effective positioning of said valve, and means for varying said connections to change the phase relationship between said motor and valve whereby the extent of rapid traverse movement of the motor may be variably determined.

16. In a machine tool having a work support and a tool support, power operable means for effecting relative movement between the supports including a first hydraulic motor, a servo-motor valve mechanism for controlling the feeding movement of said hydraulic motor, a second hydraulic motor for operating said servo-motor mechanism, and means for controlling the rate of actuation of said second motor including an adjustable feed rate determining valve, a rapid traverse selector valve, operative connections between the second hydraulic motor and said last-mentioned valve for controlling effective positioning of said valve, and a hydraulic actuating circuit interconnecting said second hydraulic motor and said valves, said circuit including a by-pass conduit whereby the same may be selectively effective on the motor by way of or exclusive of the rate control valve.

17. In a machine tool having a work support and a tool support, power operable means for effecting relative movement between the supports including a first hydraulic motor, a servo-motor valve mechanism for controlling the feeding movement of said hydraulic motor, a second hydraulic motor for operating said servo-motor mechanism, and means for controlling the rate of actuation of said second motor including an adjustable feed rate determining valve, a rapid traverse selector valve, operative connections between the second hydraulic motor and said last-mentioned valve for controlling effective positioning of said valve, a hydraulic actuating circuit interconnecting said second hydraulic motor and said valves, said circuit including a by-pass conduit whereby the same may be selectively effective on the motor by way of or exclusive of the rate control valve, means for reversing the operative effect of the hydraulic circuit as respects the motor, and a pilot circuit including a pilot valve intermittently actuatable by said second hydraulic motor for determining the effective position of said reversing means.

18. In a machine tool having a work support and a tool support, power operable means for effecting relative movement between the supports including a first hydraulic motor, a servo-motor valve mechanism for controlling the feeding movement of said hydraulic motor, a second hydraulic motor for operating said servo-motor mechanism, and means for controlling the rate of actuation of said second motor including an adjustable feed rate determining valve, a rapid traverse selector valve, operative connections between the second hydraulic motor and said last-mentioned valve for controlling effective positioning of said valve, a hydraulic actuating circuit interconnecting said second hydraulic motor

and said valves, said circuit including a by-pass conduit whereby the same may be selectively effective on the motor by way of or exclusive of the rate control valve, means for reversing the operative effect of the hydraulic circuit as respects the motor, and a pilot circuit including a pilot valve intermittently actuatable by said second hydraulic motor for determining the effective position of said reversing means, said pilot circuit including a serially arranged tarry mechanism for effecting a delayed reaction of the pilot valve on the reversing valve.

19. In a machine tool having a work support and a tool support, power operable means for effecting relative movement between the supports including a first hydraulic motor, a servomotor valve mechanism for controlling the feeding movement of said hydraulic motor, a second hydraulic motor for operating said servo-motor mechanism, and means for controlling the rate of actuation of said second motor including an adjustable feed rate determining valve, a rapid traverse selector valve, operative connections be-
